MARCEL DE CONINCK, OF LE HAVRE, FRANCE.

MULTIPLE-BLADE HELICOIDAL PROPELLER.

Application filed April 29, 1920. Serial No. 377,493.

To all whom it may concern:

Be it known that I, MARCEL DE CONINCK, of 46 Rue Felix-Eaure, Le Havre, France, engineer, have invented new and useful Improvements in a Multiple-Blade Helicoidal Propeller, which improvements are fully set forth in the following specification.

From consideration of a theoretical screw propeller with infinitely thin blades it is seen that the angle of incidence of the liquid on the blades or the angle of attack is very small for a moderate amount of slip. For example, for a slip of 15% the sine of the angle of attack will vary from .05 to .075, 15 the maximum value corresponding to that part of the blade whose inclination is about 45°.

In screws of the usual form in which the angle of the leading edge of the blade is substantially greater than the angles of attack mentioned above, the back of the blade, in the case of a moderate slip, will be subject to a pressure, the effect of which is obviously detrimental to efficiency, seeing that 25 to obtain a given pressure the slip must be increased and this reduces the efficiency.

The object of the present invention is to provide a screw propeller which shall have an increased efficiency and at the same time 30 which possesses great damping power. The blades of propellers constructed in accordance with this invention are of fusiform section and have the angle of their leading edges of the same order as the angle of attack corresponding to a moderate slip and are connected together by rings so as to form a rigid whole. Owing to the absence of objectionable pressures on the backs of the 35 blades the slip necessary for a given thrust with a screw of given diameter will be diminished and the efficiency of the screw improved in proportion. The rings are necessary for imparting the desired rigidity to the blades which are very thin. Their number, arrangement and dimensions will be so chosen as to ensure a sufficient strength. Probably the number of blades is so great 40 that the width of the blades can be reduced. This is of importance from the point of view of the utilization of the propulsive section (that is to say, of the section of the cylinder circumscribing the propeller) by reason of the diminution of the radial dispersion of the streams of liquid. Further, 45 by reducing the width of the blades the reaction which they exert on the hull which

is already considerably diminished if the slip is moderate, is felt at a smaller distance, which permits, without fear of increased vibrations, of diminishing the distance between the tips of the blades and the hull, and consequently a greater diameter and a larger propulsive section may be given to the propeller. The slip will then be less for a given thrust, and efficiency will 60 be increased, or, for a given slip the thrust will be increased.

The width of the blades decreases from the boss to the tips so as to reduce the losses which are due to friction of the water and 70 which occur mostly at the tips of the blades.

Preferably the section of the blades is double convex and symmetrical so that the thrust is made up in substantially equal proportions of a pressure on one face of the 75 blade and a reduction of pressure or reversed pressure on the opposite face. These pressures will be nearly universal over the whole length of the blade contrary to what happens in screws of the usual form where 80 the proportions of these pressures may be very unequal and may give rise to the phenomenon of cavitation if the decrease of pressure in certain regions exceeds the pressure of the atmosphere.

With a screw constructed in accordance with this invention, and having small slip, cavitation will be practically eliminated and the propeller may have a large capacity for overload, that is to say, in case of need a 90 thrust considerably in excess of the thrust during normal working can be obtained, if the engines are capable of generating substantial overload power. Another advantage in a propeller with a small slip resides 95 in the substantial lessening of the suction effect exerted by the screw on the hull. Moreover, with this type of propeller the energy of the waves can be caused to contribute to the propulsion by making the 100 speed and the torque of the engines vary in synchronism with the waves.

A propeller made according to this invention and having annular rings, exerts a very favourable influence on the sea-going qualities of the ship. These rings in effect possess a very great tendency to lessen the rolling motion of the ship, especially if the ship is provided with several screws, the rolling being rapidly damped. The efficiency of the 105 propeller so far as the damping is concerned will be far superior to that possessed by the 110

means usually employed for damping, and in particular anti-rolling keels. These latter having their length practically parallel to the direction of the streams of water give for 5 a speed of oscillation v a damping force per unit of surface proportional to v^2 , but the rings of the propeller being disposed normally to the streams will give a force per square metre proportional to the speed V of 10 the ship and to the speed of oscillation v , that is to say, proportional to Vv or $v^2 \times \frac{V}{v}$.

With equality of surface the advantage relatively to anti-rolling keels will be measured 15 by the ratio $\frac{V}{v}$, which will rarely be less than 10, and of which the value will be so much the greater as the amplitude of roll is less and the speed of the ship is greater.

20 Moreover, the effect of damping exerted by the propeller on the pitching of the ship will be very efficient. The bridge of the ship will remain practically parallel to the surface of the swell. There will result from it 25 a sensible reduction of the excess of power necessary to maintain speed in heavy weather and a possibility of increasing the mean speed of the ship.

The ship, when fitted with a propeller 30 made according to this invention may have fine lines without detriment to the maintenance of speed in heavy weather. This results in economy in the power necessary for propulsion.

35 Even when the ship is at anchor, the rings of the propeller will ensure a considerable damping effect on the rolling by their action on water agitated by a swell.

40 Amongst other advantages can be cited the checking of falling off at the moment of movement of the helm and the reduction of yawing.

45 In the accompanying drawing Fig. 1 is an end view and Fig. 2 a section through the axis of a propeller having a plurality of blades according to this invention.

50 Figs. 3 and 4 are detail views of a portion of a blade and ring, Fig. 3 being an elevation and Fig. 4 a section on the line A—B, Fig. 3. Fig. 5 is an explanatory diagram 55 illustrative of the principle involved in the shape of the propeller blade. The thicknesses have been exaggerated in the drawing for the sake of clearness. The angle of acuteness which varies according to the distance from the axis of the section considered is represented by α .

60 The propeller consists of a certain number of blades a whose width (Fig. 2) increases from the periphery to the centre. These blades are of fusiform section, preferably symmetrical (Fig. 4) having a very small angle of acuteness, of the order of the angle of attack corresponding to a small slip.

65 Referring to the diagram Fig. 5:

Take for example a section AB of a propeller blade of an infinitely small thickness. Let BC represent the tangential speed of said section AB, and let CD represent the ship's speed v . The relative speed of the water with respect to the section AB is given by BD, forming with AB the angle γ , generally known as the angle of attack.

70 For a given ship's speed, the said angle of attack will be greater, the greater the tangential speed of the section AB. This angle of attack, and consequently the specific thrust of the section AB, become zero when the tangential speed is equal to BC', such that the point D becomes D', situated on the prolongation of AB.

75 The ratio $\frac{C'C}{BC}$ gives what is known as the slip. If this ratio is low, the angle of attack γ will be very small. In practice, the 80 blade must have a certain thickness and the section is more or less a segment of a circle. For a proper working of the propeller, it is desirable that the relative speed of the water should be tangent to the back of the blade, 85 in order to avoid a negative thrust, i. e., the angle of acuteness α of the blade's edge should be equal to the angle of attack.

90 One of the characteristics of my propeller is the use of blades of small thickness in relation to their width, such that the angle of acuteness differs but slightly from the angle of attack γ corresponding to a low value of C'C. 95 The ship BC. It is known that the theoretical efficiency is greater, the smaller the value of the slip. For instance, if the slip ratio C'C is equal to 10%, the theoretical efficiency BC is equal to 100—10=90%.

100 The blades are connected to each other by annular rings b also preferably of fusiform section, fixed to the blades in any suitable manner, for example, by autogenous welding.

110 In Fig. 3, the blades are formed of segments having a helicoidal surface such as a' mounted and fixed by autogenous welding between two rings b , the successive segments of the blade such as a'' being of greater width as they approach the centre. 115 Claims:

1. In a helicoidal propeller, the combination of a large number of thin blades of fusiform section and a plurality of rings connecting the blades. 120

2. In a helicoidal propeller, the combination of a large number of thin blades of fusiform section having an angle of acuteness of the same order as the angle of attack 125 corresponding to a small slip, and a plurality of rings connecting the blades.

3. In a helicoidal propeller, the combination of a large number of thin blades of fusiform section and of increasing width 130

from the tip to the root and a plurality of rings connecting the blades.

25

4. In a helicoidal propeller, the combination of a large number of thin blades of fusiform section having an angle of acuteness of the same order as the angle of attack corresponding to a small slip and of increasing width from the tip to the root and a plurality of rings connecting the blades.

10 5. In a helicoidal propeller, the combination of a large number of thin blades of fusiform section, each blade being formed of a plurality of segments, and a plurality of rings connecting each segment of one blade to the corresponding segment of the other blades.

15 6. In a helicoidal propeller, the combination of a large number of thin blades of fusiform section having an angle of acuteness of the same order as the angle of attack corresponding to a small slip, each blade being formed of a plurality of segments, and a plurality of rings connecting each seg-

ment of one blade to the corresponding segment of the other blade.

7. In a helicoidal propeller, the combination of a large number of thin blades of fusiform section and of increasing width from the tip to the root, each blade being formed of a plurality of segments, and a plurality of rings connecting each segment of one blade to the corresponding segment of the other blades.

30

8. In a helicoidal propeller, the combination of a large number of thin blades of fusiform section having an angle of acuteness of the same order as the angle of attack corresponding to a small slip and of increasing width from the tip to the root, each blade being formed of a plurality of segments, and a plurality of rings connecting each segment of one blade to the corresponding segment of the other blades.

35

In testimony whereof I have signed this specification.

MARCEL DE CONINCK.
